UNITED STATES PATENT OFFICE

WILLEM JOHANNES DOMINICUS VAN DIJCK, OF THE HAGUE, NETHERLANDS, ASSIGNEE
TO NAAMLOOZE VENNOOTSCHAP: GLASFABRIEK "LEERDAM" VOORHEEN JEEKEL,
MIJNSSEN & CO., OF LEERDAM, NETHERLANDS

LIGHTING FIXTURE

Application filed February 15, 1929, Serial No. 340,135, and in the Netherlands February 13, 1928.

The present invention relates to lighting fixtures and has for its purpose to meet all requirements for obtaining an economical illumination, restful to the eye and not 5 fatiguing.

To obtain a good illumination, it is essential, first of all, that the rays of light of great intensity be prevented from striking the eye, particularly if the direction of these 10 rays nearly coincides with rays coming from the object to be viewed.

These difficulties are for the greater part overcome by the application of indirect illumination, but this manner of illumination 15 is monotonous as a consequence of the lack of shade, and its luminous efficiency is small.

Though sharp contrasts must be avoided, it is desirable, for the efficiency of the eye, to give the location of the object to be viewed 20 a greater intensity of light than the other parts of the lighted room.

Refractive and totally reflective prisms have also been used, bringing about, however, an inconvenient glittering of these 25 prisms; and moreover the light-distribution does not meet all requirements. A further drawback is that the prisms very soon get dirty, which impairs the efficiency.

By applying reflecting screens which surround the source of light, a good effect on the eye has been obtained in some cases, with the disadvantage, however, that intense changes 30 of light arise, while the efficiency of the lighting fixture is generally insufficient.

Further, as a result of irregularities in the fixture, dark and light spots may appear in the range to be illuminated, while troublesome light-reflections often occur on shining 35 objects.

The considerations, on which the invention is based, so as to avoid the above mentioned disadvantages are the following:

1. Obtaining a high efficiency of the lighting fixture;
2. Obtaining a high efficiency of the eye, i. e. those parts of the room, which must be seen most clearly, should have the most intense illumination, whereas blinding must be entirely prevented;
3. The room must be illuminated locally in

a uniform manner, so as to avoid intense changes to light;

4. As far as indirect illumination is applied, some shade-action should be obtained.

It has been attempted to avoid the appearance of abrupt changes in light-intensity by placing an opal or dulled plate under the reflector which, however, causes the disadvantage of undesired absorption, while rendering it difficult, if not impossible, to control the direction of the light.

The lighting fixture, according to the invention, is in the first place characterized by the specific shape of the casing or screen surrounding the source of light. This shape is so chosen that the rays either emanate from the source or, coming directly from the source, pass the openings of the fixture, or after having only once been reflected by a reflector, pass these openings or the space

between the source of light and the reflectors, or both the openings and the aforesaid space.

The shape of the casing or screen may be calculated mathematically or can be fixed in a geometrical constructive way. This problem has no special difficulties for one skilled in the art.

It is thus possible to accommodate the shape of the casing or screen to the shape of the room or space to be illuminated, so that it is not necessary that the screen be shaped as a rotation-body.

In this manner a lighting fixture is obtained which renders an intense and at the same time agreeable illumination, even if provided with a source of light less strong than might be expected, so that the great efficiency of the modern incandescent lamp manifests itself completely, as practically no light is lost on account of rays returning to the source, or on account of rays decreasing in intensity by repeated reflection, or on account of absorption or in another way.

Another characteristic of the invention is to be seen in the way in which sharp changes are avoided between regions to be illuminated with different intensities. To this end, the surfaces of the reflectors are provided with unevennesses of a very small cur-

vature which, at the same time, must preferably be finely divided.

In this manner an effect is obtained which, according to the invention, is indicated by the term "directed diffusion" and consists in that a small incident beam of light is reflected as a cone with only a small top angle.

This must be distinguished from the known manner of diffusing by a reflecting surface, for example, the known dulled glass, for in that case the rays falling on the mirror are reflected to all sides, owing to which the special shape and sizes of the reflecting casing or screen would lose their special effect, since a part of these reflected rays would fall back on the source of light or on the mirror.

The "directed diffusion" produces therefore a new technical effect, while retaining the effect obtained by the principal characteristic.

When the shape of the casing or screen is fixed according to the principal characteristic in an analytic or graphic way, sufficient liberty is still left for giving these parts of the casing or screen which throw light on a plane serving for indirect illumination, such a form that an important part of the light, falling on the said plane, is concentrated on a small part thereof.

Hence it follows that some shade-action still occurs in that part of the room which is indirectly illuminated, giving a relief effect and being agreeable to the eye.

These characteristics and some other features will be better understood from the following description, taken in connection with the accompanying drawings, in which, by way of example, an embodiment according to the invention is illustrated.

Fig. 1 is a diagrammatic top-view of a table, indicating the light-distribution obtained with the lighting fixture of the invention;

Fig. 2 shows a general view of the course of the beams of light with the device according to the invention;

Fig. 3 shows the light-distribution;

Fig. 4 shows a fixture for indirect illumination, of which

Fig. 5 represents the light-distribution-curve.

With the illumination of the table-plane according to Fig. 1, the light is divided in such a manner that the middle part of the table is less intensely illuminated than a ring-shaped part 3 around it. 1 is the lighting fixture suspended above the table; 2 is the middle part of the table, which is less intensely illuminated than the ring-shaped part 3, where the light-intensity has reached a maximum, and extending over the table.

Besides the principal illumination of part 3, a faint general-illumination must be obtained. The way in which the light-distribution is obtained, is indicated in Fig. 2, in

which the fixture is indicated in section. The adjacent parts of the fixture are indicated at 9 and 10, 8 is the source of light, and 11 is the table. The middle part of the table 11 is exclusively illuminated by rays directly originating from the source of light 8, which part is limited by the cone 12-12.

Inside this cone the rays fall, directly originating from the source of light, as well as reflected rays, and therefore the strongest light intensity prevails therein. Such a reflected ray is indicated here at 14.

Outside the area limited by the cone 12, lies an annular part or surface, exclusively illuminated by the rays, such as 15, reflected by the part 9, and not by direct rays. In case directed diffusion is utilized, a ray is emitted from each point of the casing or screen. This is indicated in the drawing by the rays 14, 15, 16 and 17, also to be indicated as bundles of rays 14'-14', 15'-15', 16'-16' and 17'-17'.

From Fig. 2 it follows that the rays reflected by the casing no longer strike the source of light from which absorption might arise, as said rays are only once reflected.

The shape of the fixture is such that more light is reflected in downward than in upward direction, since the part 9 is larger than the part 10. The downwardly reflected rays principally strike the bright ring 3 (Fig. 1) on and around the table, whereas the upwardly reflected rays for the greater part fall on a small spot of the ceiling situated vertically above the fixture (see for example the rays 16 and 17).

The light distribution-curves are represented in Fig. 3, measured in a room of 3.35×5 meters by 3.30 meters high. The source of light is a lamp of 75 watts. In this figure, 1 is the fixture, 11 the table, 18 the bright spot on the ceiling above the fixture, and 19 an object on one of the walls which casts a cone of shade 20.

The light intensity amounts to 160 lux on the middle part of the table 11, whereas the intensity amounts to over 200 lux in the brighter illuminated ring 3, represented in Fig. 1.

A lux-meter (not shown), mounted horizontally, indicates about 14 lux on the wall. The height of the fixture is 26 cm.; the lower part or bottom side of said fixture is 80 cm. above the table surface, while latter is 75 cm. above the floor.

As there are no light-losses, other than on the reflecting planes, which can give an efficiency of 80%, whereas other light losses at the utmost occur on account of small constructional imperfections, for example, along the line on which the two bent planes meet or in the edges, an exceptional high efficiency of the source of light is obtained.

As only about half of the light is reflected here and the other half is emitted directly, an efficiency of nearly 90% of the source of light

may be obtained, the illumination being very steady and not fatiguing.

From Figures 2 and 3 it is clearly to be seen that the eyes of a person in the room, either standing or sitting at the table, can never be struck by a direct ray or a ray reflected by the casing or screen. The illumination of 14 lux on the wall appears to be sufficient. For the rest, these light-intensities may be varied by altering the dimensions of the casing or screen.

The fixture according to the invention may be made of such a material that a "directed diffusion" occurs. This is attained by silver-plating the outside of the fixture, made, for example, of glass and provided with an opaque layer of lacquer. The inside of the fixture is dulled and is afterwards etched again.

Owing to this operation, a small amount of diffusion occurs with the reflection, rendering the direction of the rays a bit less sharp, without the light dispersion becoming such, however, that the light-direction can no longer be controlled.

The construction can also be different, provided that the required conditions be satisfied. In general, the casing or screen may be made of a transparent material, reflecting the light at the outside, whereas the material is dulled at one or at both sides or treated in such a manner that it also has the property that each point of the surface diffuses the rays.

In Fig. 4 a fixture according to the invention is illustrated, serving for indirect illumination of a room.

On the side wall three parts in section 18, 19 and 20 are to be distinguished, which become merged. The part 20 closes the fixture at its lower end. The source of light 8 first of all emits a direct cone, limited by the lines 21, illuminating the middle part of the ceiling 22. Rays are reflected by the part 19, a bundle of these rays being indicated at 23, whereas the bottom part 20 reflects rays, indicated by 24, illuminating an annular portion or area of the ceiling 22; rays coming from the side part 19 also partly illuminate the same.

The upper part 18 is a little more bent than the part 19 under it and reflects the bundle 25.

Thus the effect is again obtained that the light intensity is strongest in the middle of the ceiling and decreases toward the sides, practically ending in zero, while no sharp changes occur.

The light distribution-curve is indicated in Fig. 5.

The middle part 26 of the ceiling has the best luminous surface and gives the objects in the room some shade, whereas the screen itself causes a half shade cone, indicated by the lines 27.

With a view to reduce the shade of this

cone, the light is not concentrated in a very small spot, e. g. about the size of the casing, but over a plane larger than the casing itself and divided as indicated by the dotted light-distribution curve. In order to avoid the disadvantage of less sharp shade-action, it is possible to eliminate this action by making the part 20 of the fixture transparent, so that a direct cone 28—28 is formed, practically coinciding with the half-shade cone 27—27.

In that case the form of the casing must be altered a little, so that from 19—18 a little more flattened part arises and the light is concentrated more straight above the lamp. In that case a light-distribution curve occurs as indicated in a full line.

Finally, it should be observed that, according to the invention, the phenomenon by which the rays coming from a certain point of the mirror are all situated inside a cone with a small top angle, the axis of which is located in the normal reflecting-direction, may also be obtained in another way.

As explained above, the directed diffusion was obtained by providing the surface of the reflecting casings or screens with unevenesses of very small curvature, which unevenesses must preferably be finely divided.

I claim:—

1. A lighting fixture comprising an incandescent lamp, and a light-reflecting casing surrounding the same and provided with a top opening; said casing embodying distinct upper and lower, convexo-concave ellipsoidal portions disposed with their concave surfaces turned toward each other, so that the rays emitted by the lamp and impinging against the surface of the bottom portion will be reflected by the latter a single time only and will pass through said opening, while avoiding the lamp; one focus of the ellipsoidal parts being disposed at the center of the incandescent lamp.

2. A lighting fixture comprising an incandescent lamp, and a light-reflecting casing surrounding the same and provided with oppositely-located top and bottom openings; said casing embodying distinct upper and lower convex-concave portions disposed with their concave surfaces turned toward each other, so that the rays emitted by the lamp and impinging against said surfaces will be reflected by the latter a single time and will pass through both openings, while avoiding the lamp.

3. A lighting fixture according to claim 2, in which the convexo-concave portions of the casing embody ellipsoidal parts, one focus of which is disposed at the center of the incandescent lamp, while the other focus is located near one of the casing openings.

In testimony whereof I affix my signature.
WILLEM JOHANNES DOMINICUS van DIJCK.
